A. C. BENNETT

ADJUSTABLE PIPE HANGER

Filed Sept. 26, 1925

INVENTOR
ASHER C. BENNETT
By *Arthur L. Sree*
ATTY.

UNITED STATES PATENT OFFICE.

ASHER C. BENNETT, OF SAN FRANCISCO, CALIFORNIA.

ADJUSTABLE PIPE HANGER.

Application filed September 26, 1925. Serial No. 53,919.

My invention relates to improvements in adjustable pipe hangers wherein a vertically disposed bracket having a gooseneck on the upper portion thereof is arranged to be embedded within a concrete ceiling while said ceiling is being formed, and operates in conjunction with a turn buckle to adjust the position of a pipe relatively to said ceiling.

The primary object of the present invention is to provide a new and improved adjustable pipe hanger as a new article of manufacture.

Another object is to provide a new and improved device of the character described, composed mainly of standard parts, such as turn buckles, pipe sections and caps therefor, and standard rods.

A further object is to provide a device of the type set forth which may be produced cheaply and which shall have a maximum efficiency.

A still further object is to produce a simple, cheap and effective adjustable pipe hanger by means of which a pipe may be easily suspended from a ceiling at the required elevation or inclination, and also by means of which a pipe may be easily placed or removed.

The invention consists in the details of construction disclosed in the drawings forming a part of the present specification wherein like characters of reference are used to designate similar parts throughout said specification and drawings, and in which—

Fig. 1 is a broken elevation, partly in section, of my improved adjustable pipe hanger, also showing a portion of a concrete ceiling and a portion of the concrete form therefor;

Fig. 2 is a side view of Fig. 1; and

Fig. 3 is a transverse sectional view taken on line 3—3 of Fig. 1 in the direction indicated.

Referring to the drawings the numeral 1 is used to designate what I term, for purposes of illustration, a vertically disposed bracket having a screw-threaded portion 2 on the lower end thereof. The upper portion of the bracket 1 is provided with a gooseneck portion 3 whose outer end 4 is arranged to lie upon the upper surface of the concrete ceiling form 6 and is provided with a suitable aperture 7 by means of

which a nail or screw 8 may be employed to rigidly connect said gooseneck to said form 6 while the concrete 9 is being poured to form said ceiling, by means of which arrangement the gooseneck 3 is held in spaced relation to the said form 6 to permit the said concrete to flow around and thus embed the said gooseneck 3 to support the bracket 1 vertically after the concrete has set and the form 6 has been removed.

Screw threaded upon the lower screw-threaded portion 2 of the bracket 1 I have provided a standard stirrup or turn-buckle 11 having an aperture 12 therein, within which aperture 12 is slidably and rotatably mounted a short vertically disposed standard pipe section 14 screw-threaded at both ends. To the upper end of said pipe section 12 is screwed a standard pipe cap 16 which acts as a nut or bushing to rotatably support the pipe section 14 within the lower portion of the stirrup or turn-buckle 11.

The lower end of the pipe section 14 is screw threaded into a ring 17 which ring 17 is arranged to engage a pipe 18 to be supported.

In operation, after the forms 6 are in position and before the concrete 9 is poured, the brackets 1 are positioned by projecting the vertically disposed portions 1 through suitable apertures 19 which have previously been bored through said forms at the required intervals, with the free ends of the gooseneck portions 3 resting flatly upon said forms 6, with the curved or goosenecked portions 3 partly in spaced relation to the bottom of the form 6 as disclosed in Fig. 1 of the drawings. The bracket is temporarily secured in this position by driving a nail or other suitable securing element or member 8 through the aperture 7 in the end 4 and into the form 6. This will hold the main portion of the bracket vertically disposed, as required, until the concrete ceiling 9 has been poured and set, thus embedding the curved or gooseneck portion 3 of the bracket 1 firmly within the concrete ceiling with the main or vertically disposed portion 1 of the bracket firmly in a correct position.

After the ceiling has set and the forms 6 have been removed, leaving the rods or brackets 1 depending vertically from said ceiling, the stirrups 11 are screwed onto the

threaded portion 2 of the bracket 1. The rings 17 are next mounted upon the pipes 18 and the pipe sections 14 are screwed into position and inserted through the aperture 12 of the stirrup 11 and the pipe caps 16 screwed firmly into position. Or the pipe sections 14 may be inserted through the aperture 12 of the stirrup 11 with the pipe cap 16 in place and the lower end of said pipe section may then be screwed into the ring 17.

When the proper connections between the several parts have been made, the position of the pipe horizontally or in an inclined position for drainage purposes may be readily adjusted by rotating the stirrup 11 until the adjacent pipe 18 is in the required position.

The clearance between the bottom of the vertically disposed rod 1 and the cap 16 is sufficient to permit an upward movement of the stirrup 11 for adjustment purposes. This clearance also readily permits the removal upwardly of the pipe section 14 and cap 16 thereon when required.

It is obvious from the foregoing that I have provided a new and improved article of manufacture comprising an adjustable pipe hanger of maximum efficiency and adjustability and having few parts of simple standard construction which may be economically produced and replaced when required.

Having thus described my invention what

I claim as new and desire to secure by Letters Patent is—

1. As a new article of manufacture, a pipe hanger comprising a vertically disposed rod threaded at its lower end and having a lateral extension arranged to be embedded within a concrete ceiling; a turnbuckle screw-threaded to the lower end of the vertically disposed rod; a ring arranged to engage a pipe to be supported; and means pivotally connecting the ring with the lower end of the stirrup whereby said ring may be adjusted relatively to the ceiling when said turnbuckle is rotated upon the threaded rod.

2. As a new article of manufacture, a pipe hanger comprising a vertically disposed rod threaded at its lower end and having a lateral extension arranged to be secured to the inside of a ceiling form; a turnbuckle screw-threaded to the lower end of said rod and having an aperture in the lower end thereof; a ring arranged to engage a pipe to be supported; a pipe screw-threaded into the top of the ring and extending through the aperture in the lower end of said turnbuckle and a pipe cap screw-threaded onto the top of said pipe to pivotally connect the same to said turnbuckle whereby the length of said pipe hanger may be adjusted when said turnbuckle is turned upon the threaded portion of the vertically disposed rod.

In witness whereof I hereunto set my signature.

ASHER C. BENNETT.
